UNITED STATES PATENT OFFICE.

LAWSON L. ROBERTS, OF CHILTON, TEXAS.

PORTABLE TOILET OR CONVENIENCE.

Application filed February 15, 1927. Serial No. 168,429.

This invention relates to portable structures consisting of a frame and a canvas or other fabric cover and the general object of the invention is to provide a tent-like structure which may constitute a tourist toilet or rest room.

Another object is to provide a structure of this character rectangular in plan and which is formed of a collapsible frame which may 10 be readily folded up to be carried and which may as readily be unfolded and set up.

A further object is to provide a collapsible frame of this character which will support the tent structure so as to provide the roof 15 thereof with the proper pitch to permit rain to run off.

A still further object is to provide a structure of this character having corner posts which may be forced into the ground.

20 Other objects will appear in the course of the following description.

My invention is illustrated in the accompanying drawings wherein:—

Figure 1 is a perspective view of a portable structure constructed in accordance with 25 my invention;

Fig. 2 is a fragmentary end elevation of the tent supporting structure;

Fig. 3 is a fragmentary side elevation of 30 the same;

Fig. 4 is a like view to Figure 2 but showing the structure partially collapsed;

Fig. 5 is a fragmentary face view of the end of one of the main braces;

35 Fig. 6 is a like view to Figure 5 but of the complementary brace;

Fig. 7 is a horizontal section through the conjoined ends of the main braces;

Fig. 8 is a vertical section through the 40 conjoined ends of the main braces.

Referring to these drawings it will be seen that the frame consists of four main corner posts designated 10. These posts are arranged about 3' apart though any other suitable dimensions may be used. The posts are preferably between 5 and 6' high and may be made of angle iron or have any other cross section. The lower ends of the posts

are pointed so that they may be forced into the ground. One of these posts which is 55 identified by the exponent "a" applied to the numeral 10 constitutes the right side door post for the front of the structure.

Each pair of posts is connected by links or braces 11 and 12 pivoted to the corresponding post at 13, and pivoted to each other at their adjacent ends. Preferably one of these bracing links as, for instance, the link 11 is formed with an elongated groove 13^a while the other link is formed with an elongated projection or lug 14 adapted to fit in the groove 13^a. A pivot pin 15 in the form of a small bolt passes through the overlapped ends of the links and through the aperture in the recess 13^a and in the lug 14 and a coiled 60 compression spring 16 fits around this bolt, bearing at one end against a stop 17 and at the other end bearing against the inner link. This spring, therefore, acts to force the lug 14 into the recess or slot 13^a when the two 65 links are disposed in alignment with each other and thus lock the two links in this alignment. Preferably one of the links, as the link 11, has a laterally projecting lug 18 which extends beneath the other link 12 70 so that the links cannot break upward.

From each post and the bracing link 11 which is pivoted thereto, extend the braces formed of the links 19 and 20. These links are pivoted at their extremities to the post 80 and link 11 respectively and pivotally connected to each other in the same manner as are the links 11, that is, the conjoined ends of the links 19 and 20 are provided one with a recess and the other 85 with a lug and a spring urges the lug into the recess so as to lock the links in aligned relation. These links are also adapted to break downwardly and when they are in aligned relation act to support the main 90 links 11 or braces against downward thrust. In order to hold the top or roof of the canvas cover in position to provide a ridge, I mount upon the rafter braces formed by the links 11, the two pairs of links 21 and 22. 95 These are pivoted at 23 to the respective links

11 and are pivoted at their outer ends to each other, as at 24, and preferably one of the links as, for instance, the link 21, is laterally bent at its upper end so as to provide a 5 flattened portion 25 which will support the canvas at the ridge and prevent the canvas from being punctured or worn at this part. These ridge braces 21 and 22 are disposed opposite each other at opposite sides of the 10 structure so that the ridge of the roof runs parallel to the front of the structure.

Each of the corner posts is provided at its upper and lower ends with outwardly 15 projecting buttons 26 whereby the canvas cover may be attached to the posts and the post 10^a is not only provided with these buttons 26 but with inwardly projecting buttons 27 at the lower end of the post and at the middle thereof and an 20 outwardly projecting button 28 at the middle of the post.

The canvas cover 29 may be formed of 25 separate panels buttoned to the buttons 26 or may be sewed around three sides and at the top, so as to provide three walls and a roof portion. The front wall 29^a of the canvas cover is intended to be buttoned at its upper end and free edge to the upper button 26 on the post 10^a and is provided 30 with button holes 30 on its free edge whereby it may either be buttoned to the lower button 26 and the button 28 or buttoned on the inside to the buttons 27. Thus this door 35 may be opened and closed either from the outside or inside. Preferably one of the posts is provided with a paper rack or holder 31.

It will be seen that the structure described 40 may be made of very light material and that when it is folded it will be in compact form for easy transportation and that it may be readily set up at any place desired and that when so set up the corner posts are strongly 45 braced not only to support the weight of the canvas cover but to support the structure as a whole against the action of wind. I do not wish to be limited to the details of construction and arrangement of parts illustrated as it is obvious that many changes 50 may be made therein without departing from the spirit of the invention as defined in the appended claims.

I claim:

1. A portable folding structure of the 55 character described including four corner posts, main braces connecting the corner posts with each other, each brace being formed of two links pivoted to the respective corner posts and to each other, means 60 locking the links in a position of alignment when the links are in a horizontal position, auxiliary braces each formed of two links respectively pivoted to a post and one of main links and having means for locking 65 them in alignment with each other and ex-

tended diagonally from the post to the corresponding link of the main brace when the main braces are horizontal, and ridge supports consisting of two pairs of links pivoted to each other and to the links of the 70 main braces inward of the outer ends thereof and extending upward convergently when the main braces are horizontal, and a tent adapted to enclose and be supported by said structure and having a roof portion engageable with the ridge supports, the tent structure having one wall thereof adapted to be opened or closed.

2. A portable folding structure of the character described including four corner 80 posts, main braces connecting the corner posts with each other, each brace being formed of two links pivoted to the respective corner posts and to each other, means locking the links in a position in alignment 85 when the links are in a horizontal position, auxiliary braces each formed of two links respectively pivoted to a post and one of the main links and having means for locking them in alignment with each other and 90 extended diagonally from the post to the corresponding link of the main brace when the main braces are horizontal, and ridge supports consisting of a pair of links for each main brace, the links of each pair being 95 pivoted to each other and to the links of the main braces inward of the outer ends thereof and extending upward convergently when the main braces are horizontal, and a tent adapted to enclose and be supported by 100 said structure and having a roof portion engageable with the ridge supports, the tent structure having one wall thereof adapted to be opened or closed, one of the corner 105 posts having buttons on the inside and outside of the post whereby the free edge of said last named wall may be buttoned either from the inside or outside.

3. A portable foldable structure of the character described including four corner 110 posts having pointed lower ends, main braces connecting each corner post with adjacent corner posts, each main brace consisting of two links pivoted at their outer ends to respective posts and at their inner ends to 115 each other, means for locking the links of the main braces in aligned position, auxiliary braces each formed of two links pivotally connected to each other at their adjacent ends and at their outer ends respectively pivoted to a corner post and to one of the links of a main brace, means for locking the auxiliary links in aligned position, means permitting the links of the main braces and the links of the auxiliary braces 120 to break downward but preventing them from breaking upward, two oppositely disposed ridge supports each consisting of two links, the links of each support being pivoted to each other at their adjacent ends 125 130

and pivoted to the links of oppositely disposed main braces inward of the ends thereof, one of the links of each ridge support extending beyond the other link and being deflected to form a relatively flat surface, said ridge supports breaking upward, and a cover of textile fabric formed to provide four walls and a roof portion, the roof portion being adapted to be supported at its middle by the ridge supports, one of said walls having a free edge and one of the corner posts having buttons on its inside and outside for engagement with said free edge, each of the remaining posts having buttons for engagement with the walls of the cover. 15

In testimony whereof I hereunto affix my signature.

LAWSON L. ROBERTS.
